(57) **CLAIM**

The ornamental design for a low density stack chair, as shown and described.

DESCRIPTION

FIG. 1 is an isometric view illustrating a first embodiment of a low density stack chair with arms incorporating my new design;

FIG. 2 is a front elevation view thereof;

FIG. 3 is a left side elevation view thereof, the right side elevation view being a mirror image;

FIG. 4 is a rear elevation view thereof;

FIG. 5 is a top plan view thereof;

FIG. 6 is the second embodiment of the low density stack chair without arms;

FIG. 7 is a front elevation view thereof;

FIG. 8 is a left side elevation view thereof, the right side elevation view being a mirror image;

FIG. 9 is a rear elevation view thereof; and,

FIG. 10 is a top plan view thereof.
